UNITED STATES PATENT OFFICE

JOSEPH LEO HILLAN, OF AUSTIN, MINNESOTA

COMBINED GRATE SHAKER HOUSING AND LOCKING DEVICE

Application filed July 3, 1929. Serial No. 375,630.

My invention relates to a housing for the grate shaker members or levers of a locomotive fire-box whereby the usual openings in the floor or deck of a locomotive cab will be closed against the ingress of steam, cinders, dirt and the like through the usual openings necessary in the deck, thus providing means in compliance with the rules of the Interstate Commerce Commission.

One object of the invention is to provide a housing of such construction that proper operation of the grate-bar shakers may be possible, while at the same time providing a constant closure about the shaker elements which at the same time constitutes locking means for the grate shakers without, however, interfering with the comparatively compact space or room in the locomotive cab.

Another object of my invention is to provide a housing of such construction that drains from the boiler gauge cocks as well as all other drains will be discharged beneath the housing and re-entry of steam or other foreign matter into the cab will be prevented and the engine crew thus fully protected.

A further object of the invention is to provide a construction with a sliding or yieldable connection with the boiler head to compensate for the expansion of the boiler during operation.

The above enumerated objects and its advantages as well as other objects and advantages inherent in the construction, will all be readily comprehended from the detailed description of the accompanying drawings, wherein:

Figure 1 is a front elevation of my improved housing shown applied to a cab floor and to the cab wind sheets which are shown in section, with portions of the usual drain-pipes being shown.

Figure 2 is a cross-sectional view at one end of the housing, taken substantially on the line 2-2 of Figure 1.

Figure 3 is a detail sectional view taken substantially on the line 3-3 of Figure 1.

Figure 4 is a transverse sectional view taken substantially on the line 4-4 of Figure 1, with a portion of the grate-bar shaker link in elevation.

Figure 5 illustrates a modified form of the housing, in cross-section, shown applied to a type of locomotive wherein the shaker fulcrum element or bracket is differently located relative to the cab-floor.

Under the Interstate Commerce Commission rule as recently amended, it is required that all unnecessary holes or openings in the floors of locomotive cabs must be closed for the protection of the engine crew so as to prevent possibility of the enginemen being scalded by the blowing back of the hot steam and water which is drained from the gauges or other devices of the boiler and to further protect the enginemen against the inblowing of cinders, small coal particles and dust through the openings at present in the floor of a locomotive cab.

In the particular exemplification of my invention as shown in the first four figures of my invention, the housing, generally indicated at 10, is composed of pressed steel or other suitable metal and shown of arcuate or segmental formation transversely, as shown in Figures 2 and 4 and of length preferably commensurate with the width of the locomotive cab in order that the housing may extend from wind-sheet to wind-sheet 11, 11, as shown in Figure 1. The housing 10, at its opposite ends, is shown provided with the preferably inturned flanges 12 adapted to extend substantially flush with the cab wind-sheets 11 to which said flanges are shown riveted, bolted or otherwise secured as at 13.

The lower or forward longitudinal edge of the housing is flanged outwardly or secured to an angle bar as at 14, in order that this longitudinal side of the housing may be secured to the deck or cab-floor 15 in any suitable manner, as for example by bolts 16.

Locomotive fire-box grates are usually arranged in independently operable sections composed of a plurality of grate-bars linked together, and the respective sections provided with links as at 18, with each link 18 connected with a shaker lever 19, which levers are fulcrumed in suitable slotted brackets 20, secured to the boiler-head.

As these elements form no part of my invention, further detailed description and

more specific illustration beyond that contained in the drawings need not be entered into; such constructions being well known in the art.

- 5 My improved housing is therefore provided with a suitable number of openings 17 positioned in keeping with the location of the fulcrum points 21 of levers 19 on the bracket members 20, 20. In the specific exemplification, the housing is provided with a pair of large openings 17 which are covered by the slotted plates 22, 22; the plates 22, 22 being shown riveted at 23 to the main housing 10; or otherwise secured thereto against movement so as to provide a complete covering for the openings in the main housing.

20 The plates 22 are slotted transversely, as shown at 24; the slots 24 being of width to permit free passage of the levers 19 therethrough and are of length commensurate with the degree of oscillatory movement of the levers 19 necessary for complete grate-bar shaking operation.

25 The plates 22, at opposite ends and at points intermediate of the slots 24, are held in spaced relation with the main wall of the housing 10 by spacer elements or strips 25, (see Figure 3) which preferably extend through the entire length of plates 22, namely in a direction transversely of housing 10, in order to close off the space or openings between the plates 22 and the housing 10 on opposite sides of the slots 24 in plates 22, so that foreign matter may not enter the cab of the locomotive therethrough.

30 The spacing between the plates 22 and the main housing 10 is made sufficient to receive slide-plates or members 26 and permit the latter to freely slide back and forth during oscillatory movement of the levers 19 when shaking operation of the grate-bars is to be performed.

35 These slide-plates 26 are formed to fit over the levers 19, or rather are slotted as at 27 to permit the levers 19 to pass therethrough; the slots being made of size just sufficient for passage of the levers 19, so as not to leave clearance for the passage of steam or other foreign matter.

40 The plates 26 are of width and length greater than the width and length of slots 24 in plates 22, in order to at all times provide closures for these slots 24; hence the length of slide-plates 26 is such that when the levers 19 are at one end of the slots 24 in plate 22, the end of the slide-plates 26 on one side of the levers 19 will entirely close the exposed ends of the slots in the stationary plates 22, and hence prevent ingress of steam, cinders, or other foreign substance.

45 In order to compensate for the expansion and contraction of the boiler, I support the adjacent upper longitudinal side of the housing 10 by means of a bracket 28 which is secured to the boiler-head which is partial-

ly indicated by the wall 29. The bracket 28 is preferably in the nature of an angle bar which may extend throughout the entire length of the housing so as to provide a closure at the upper rear side of the housing, while at the same time yieldingly supporting the housing by the laterally extending leg or side of the angle bar bracket 28, as shown in Figures 2 and 4.

50 In Figure 5 I show a modified form of my invention as applied to locomotive fire-box wherein the arrangement of the shaker elements and location of the fulcrum bracket 20 is somewhat different; namely where the fulcrum bracket 20 is located above the deck or cab-floor 15, while the shaker lever 30 is of the angular form shown, being bent at its fulcrum point 31 so that the lower end extends substantially vertically when in normal position.

55 In order to avoid too much restriction of the cab space, the housing 32 is shown provided with a flat upward sloping wall 33 and an upper flat wall 34, which, like housing 10, is slotted at 17 for passage of the shaker levers 30 therethrough. The forward sloping wall 33 is shown flanged along its lower longitudinal edge as at 35 to extend flush with the floor 15 of the cab and to be firmly secured thereto by bolts 16 or in any other suitable manner. The upper longitudinal side of the housing 32 is also yieldingly supported from the boiler-head 29 by bracket 28, to take care of expansion and contraction of the boiler during operation, while at the same time always maintaining a closure for the juncture between the housing and the boiler-head.

60 The openings 17 in the top wall 34 of housing 32, like in housing 10, are provided with slotted plates 36 held in spaced relation with wall 34 by spacer elements or plates 25 as previously described and arranged at opposite ends of the plates 36 and between the slots 24 in plates 33 so as to also act as closures and at the same time permit free sliding movement, between wall 34 of housing 32 and plates 36, of the slideable plates 26^a, which are made flat to correspond with the flat top of housing 32 instead of being arcuate as in Figures 1 and 4 where the housing is of arcuate formation transversely. The slide plates 26^a of the construction shown in Figure 5 have the lower ends of the levers 30 pass therethrough with the plates extending beyond opposite sides of the levers as described in connection with the previous construction.

65 This maintains a constant closure for the slots 24 in the plates 36 which are arranged over the lever openings in the main top wall 34 of the housing 32 and prevent passage of steam, cinders and other foreign matter into the cab where it would endanger the lives of the enginemen or interfere with their operations.

In order that the shaker mechanism may be held against improper movement and the grate-bars locked in normal position, I provide locking mechanism for the respective slide-plates in the nature of the headed pins 37 which are intended to be inserted in suitable holes in the housings forward of the upper ends of the slots in plates 22 in the construction shown in Figures 1 and 4, or at the rear ends of the slots 24 in the construction shown in Figure 5; the heads of the pins 37 holding the pins in place, while the shanks of the pins will be disposed in the paths of the slide-plates when the shaker levers are in normal position. That is to say, the pins will extend through the housings and be located in advance of the ends of the slide-plates 26 and thus prevent oscillatory movement of the levers which carry the slide-plates with them. The locking pins 37 are preferably shown provided with small chains 38 which are also suitably fastened to the housing to prevent their loss.

Where the type of housing shown in the first two figures of the drawings is employed, I prefer to provide the housing with a safety tread for the enginemen when stepping on the housing to work on the boiler-head, such as filling the lubricator, etc.

This safety tread is in the nature of an angle iron running full length, wherever possible, of the housing as shown at 39; the angle iron being riveted to the housing at a point which permits one leg or side of the iron to be disposed in a substantially horizontal direction.

It is apparent from the constructions shown and described that the present openings in the deck or cab-floor are entirely covered and ingress of steam, cinders and other foreign matter will be practically impossible and the rules of the Interstate Commerce Commission thus fully complied with, while at the same time permitting proper operation of the grate shaker levers, which at the same time may be locked against accidental movement. Furthermore, the structure will permit of relative movement between the boiler-head and the deck without in any way interfering with the proper functioning and operation; the housing being also formed and adapted to receive the various drains and drain-pipe guides, as shown for example at 40; and while the drawings are believed to show the best embodiments of my invention, alterations are possible and may be made without, however, departing from the spirit of my invention, which has been described in terms employed for description and not as terms of limitation.

What I claim is:

1. In a device of the character described the combination with the grate shaker levers and the wind-sheets of the cab of a locomotive, of an open bottom housing adapted to extend across the juncture between the cab floor and

the boiler head of the locomotive with the ends of the housing secured to the wind-sheets, said housing being secured to the cab floor against movement and having an opening therethrough for passage of the shaker levers, means secured to the boiler head of the locomotive and extending throughout the length of the housing whereby the housing is yieldingly supported on the boiler head and a closure between the head and housing provided, members disposed across the openings in the housing and secured in spaced relation to the housing and being slotted for passage of the levers and to permit them to be oscillated, and plates snugly fitted about the levers and slidably arranged between the housing and said members so as to move with the levers when the latter are oscillated, said plates being of width and length greater than that of the slots in said members so as to constantly close the slots in all positions of the levers.

2. A device of the character described comprising, in combination with the grate shaker levers and the wind-sheets of the cab of a locomotive, an open bottom housing arranged to extend across the juncture between the cab floor and the boiler head of the locomotive with the ends of the housing secured to the wind-sheets of the locomotive cab, said housing having openings therethrough for passage of the grate shaker levers, a member secured to the boiler head for yieldingly supporting the adjacent side of the housing and provide a closure between the boiler head and the housing, slotted members disposed across the openings in the housing and secured in spaced relation to said housing, plates snugly fitted about the levers and slidably mounted between the housing and said members and of width and length greater than that of the slots in said members so as to constantly close the slots, the members at one end of the slots having apertures, and locking pins seatable in said apertures so as to extend into the path of said plates and thereby lock the plates with the levers against movement.
